UNITED STATES PATENT OFFICE.

FRANK M. MITCHELL, OF LA GRANGE, ILLINOIS.

WASHING-MACHINE.

No. 920,977.

Specification of Letters Patent.

Patented May 11, 1909.

Application filed March 9, 1908. Serial No. 419,970.

To all whom it may concern:

Be it known that I, FRANK M. MITCHELL, a citizen of the United States, residing at La Grange, in the county of Cook and State of Illinois, have invented new and useful Improvements in Washing-Machines, of which the following is a full, clear, concise, and exact description, reference being had to the accompanying drawing, forming a part of 10 this specification.

My invention relates to washing machines for clothes and textile fabrics, and particularly to that class of washing machines which comprises a pivoted suds-box adapted to be 15 oscillated about its pivots so that a continuous movement of the water and the articles to be washed is maintained, and the object of my invention is the provision of a washing machine of this class which will be simple and 20 cheap of manufacture, as well as clean, convenient and efficient in operation.

For a full understanding of my invention, reference is to be had to the following specification and accompanying drawings, in 25 which—

Figure 1 is a front elevation of my improved washing machine; Fig. 2 is a side elevation of the same; Fig. 3 is a vertical section taken on the line 3—3 of Fig. 1, looking in the 30 direction of the arrows; Fig. 4 is a horizontal section taken on the line 4—4 of Fig. 2, looking in the direction of the arrows; Fig. 5 shows a modification of my invention, wherein is employed a device for aiding the movement of the clothes in the suds-box; and Fig. 35 6 illustrates a further modification.

Like characters of reference refer to like parts throughout the specification and drawings.

The suds-box 1 of the washing machine is 40 of substantially cylindrical shape and is provided at its upper part with a neck 2 through which the clothes are inserted. A cover 5 is provided for the neck 2. The curved wall of 45 the suds-box is bent inwardly at the parts adjacent the neck 2 so as to form curved, inwardly extending, projections 6, the purpose of which will be hereinafter described. Spider brackets 7 are riveted to the outside 50 of the suds-box. Projecting from the spider brackets 7 are pivot pins 8 which are mounted in the bearing apertures 9 of standards 10 located on either side of the suds-box. A handle 11 is attached to the side of the suds-

box, by means of which handle the suds-box 55 can be rocked to any desired extent about the pivot pins 8 in either direction.

Secured to one of the standards 10 is a vertical supporting post 12, terminating in a plane slightly below that of either of the 60 outer edges of the neck 2 when situated vertically above the axis about which the suds-box 1 is rockable. In the upper end of the post 12 is fixed a vertical pivot pin 13, which enters the pivot aperture 14 of a wringer 65 supporting bar 15 which is thus connected to the post 12 in such manner as to be capable of swinging horizontally in either direction about the pivot pin 13. The wringer supporting bar 15 has a groove 16 in its lower 70 face, and is capable of vertical movement on the pivot pin 13. The wringer supporting bar 15 may be made to retain the suds-box in a tilted position by rocking the latter until one of the upper edges of the neck 2 is vertically 75 above the axis of the suds-box, whereupon the wringer supporting bar 15 is swung around upon the pin 13 and made to engage, with its groove 16, the edge of the neck 2, the supporting bar being lifted slightly upon the 80 pin 13 to effect this.

Within the lower part of the suds-box, at right angles to the axis of oscillation thereof, are riveted a plurality of upwardly curved bars 17, the distance between the bars being 85 sufficient to allow the water to pass readily between them, but not being enough to allow any clothes to fall into the space between the bars and the lower part of the suds-box. 90

When using the washing machine, the clothes to be washed are placed, with a certain amount of soap and water, into the suds-box. The wringer supporting bar is swung backward about the bolt 13 so as to be out of the path of the suds-box, and the cover 5 is placed in position. A reciprocating movement is now imparted to the handle 11, whereby a reciprocating circumferential motion is imparted to the water, which is 100 forced by centrifugal action against the curved wall of the suds-box, which wall it follows as it flows to and fro. During the motion of the suds-box the clothes slide, with each movement, along the bars 17 from one 105 end thereof to the other, and the water, traveling in the same direction, but around the inner periphery of the curved wall of the

suds-box, impinges upon the clothes from below and subjects them to a thorough washing action. By arranging the bars 17 in the manner described, a continuous washing of the clothes on both sides is effected, without the use of beaters or other means whereby the clothes might be injured. As ordinarily constructed heretofore, washing machines of this class have been subject to the disadvantage that the water was liable to splash out around the cover of the suds-box when the machine was being operated. This disadvantage has been entirely obviated in the construction of suds-box according to my invention, by the provision of the curved projections 6 which deflect the water away from the cover 5 and toward the center of the suds-box. When the clothes are considered to be sufficiently washed, the lid is removed from the suds-box and the latter is slightly tilted. The wringer supporting bar 15 is then swung around and, as above described, made to engage, with its groove 16, the edge of the neck 2, whereby the suds-box is retained in its slightly inclined position, in which position the clothes can be very readily removed and passed through the wringer.

In the modification shown in Fig. 5, side plates 18 of wood are fixed to the lower part of the suds-box by means of bolts 19. A roller 20 is rockably mounted between the side plates 18. Adjacent the roller, and extending tangentially from either side above the axis thereof, are two perforated plates 21. The plates are riveted at one edge to the curved wall of the suds-box and form, with the roller 20, a curved surface similar to that afforded by the bars 17. The roller 20 is cut away at its under portion to allow the free passage of the water between it and the inner side of the suds-box. At the ends of the roller 20, lugs 22 are provided, on either side of the cut away portion, for the purpose of engaging the under side of the perforated plates 21 and limiting the movement of the drum in either direction. During the operation of the machine, the roller 20, the upper side of which is heavier than the lower, rocks relatively to the suds-box and aids in carrying the clothes resting upon it from one side of the suds-box to the other. The perforated plates 21 may be replaced, if desired, by rollers 23 journaled between the side plates 18 in a plane parallel to the plane of the roller 20, (Fig. 6). The rollers 23 may be of any desired number, provided enough

space be left for the free passage of the water between them, and they are arranged so as to form, with the upper surface of the roller 20, a curved surface similar to that afforded by the bars 17.

Having thus described my invention, what I claim as new and desire to secure by Letters Patent is:

1. A washing machine comprising a standard; an upwardly extending arm attached to said standard and having a vertically disposed pivot pin at its upper end; a suds box rockably connected to the standard, said suds box being formed with an opening through which the goods to be washed are inserted or removed and a neck adjacent said opening; and a horizontally disposed wringer bar having a pivot hole therein for receiving said pivot pin, said wringer bar being formed with a groove in its lower side for receiving the edge of said neck and retaining the suds box in a certain predetermined position.

2. A washing-machine comprising a standard; a suds-box rockably connected with the standard, said suds-box consisting of two side walls and a curved peripheral wall intermediate the side walls, and said suds-box being internally provided with two curved liquid-deflecting projections, and a neck between said projections; a cover for the neck; and an arched support for the articles being washed, said support consisting of a plurality of upwardly curved bars extending across said peripheral wall at the lower part of the suds-box, said bars being substantially parallel with the side walls of the suds-box.

3. A washing machine comprising a standard; a suds-box rockably connected therewith, said suds-box consisting of two side walls and a curved peripheral wall; and an arched support for the articles being washed, said support consisting of a plurality of separate upwardly curved bars extending across said curved peripheral wall at the lower part of the suds-box and being attached at their ends to said curved peripheral wall, said bars being substantially parallel to the side walls of the suds-box.

In witness whereof, I have hereunto subscribed my name in the presence of two witnesses.

FRANK M. MITCHELL.
